UNITED STATES PATENT OFFICE.

GAYLORD A. BARCLEY, OF NEWARK, NEW JERSEY.

WIRE GARMENT-STAY.

1,150,327.

Specification of Letters Patent.

Patented Aug. 17, 1915.

Application filed February 20, 1915. Serial No. 9,503.

To all whom it may concern:

Be it known that I, GAYLORD A. BARCLEY, a citizen of the United States, residing at Newark, in the county of Essex and State 5 of New Jersey, have invented a new and useful Improvement in Wire Garment-Stays, of which the following is a specification.

My invention relates to improvements in 10 wire garment stays wherein a plurality of comparatively thin wires are formed into overlapping, interlocking, and mutually supporting loops; to produce a stay without abrupt bends which has universal flexibility, 15 and the full stiffness of a stay formed of a less number of thicker wires, but without the tendency of such heavier wires with abrupt bends to crystallize and break when submitted to frequent or extreme flexure.

20 I attain these objects in the stay illustrated in the accompanying drawing, in which—

Figure 1 is a plan view, and Fig. 2 is an edgewise view of the same.

25 Similar letters refer to similar parts in both views.

I preferably employ four wires to form this stay, which I have designated *a*, *b*, and *c*, *d*; each wire is formed into semicircular loops *e*, *f*, extended lengthwise of the stay, and each semicircular loop has formed at each of its terminals a lateral oval loop *g*, *h*, also shown oppositely formed at *i*, *k*; all 30 the semicircular loops are of equal size, and 35 equally spaced apart to adapt two or more oppositely formed and oppositely placed wires, to overlap the semicircular loops *e*, *f*, alternately, and to interlock, and mutually stiffen and support the lateral oval loops 40 *g*, *h*, and *i*, *k*, when joined as shown in Fig.

45 1. Such structure affords mutual support in the alternate overlapping semicircular longitudinal loops, which is materially enhanced and stiffened by means of the interlocking of the oppositely formed transverse oval loops at each terminal of the semicircular loops.

50 It will be understood that the wires *a*, *b*, are formed into loops *e*, and *i*, *k*, and are joined to form a pair; and that the wires *c*, *d*, are also made into loops *f* and *g*, *h*, of like dimensions and equally spaced but oppositely formed also joined in a pair; so that the wires *c*, *d*, may be placed opposed

to the wires *a*, *b*, and be adapted to be 55 joined into a stay of four wires to produce the stay herein described.

It is recognized that it has heretofore been proposed to construct a stay of interlaced loops, but such proposed stays have been of 60 objectionable thickness because in the proposed assemblage of the loops the wires were arranged in pairs, so that successive 65 pairs of loops stiffened and protected succeeding pairs of loops and thus prevented the resulting stay from being flattened down to the minimum thickness. As distinguished 70 from this result, the present invention provides a series of single interlaced loops arranged in such relation that the final resulting stay is of minimum thickness, being substantially only the thickness of a single wire. The loops in this improved structure, as 75 above described, are formed from four wires arranged two at one side of the stay and two at the other side of the stay, the loops being arranged with a lap of one wire at one side of the stay succeeded by a lap of one wire at the other side of the stay, which second 80 loop is then succeeded by a loop from the second wire of the first side of the stay and that lap is then succeeded by a loop of the second wire of the second side of the stay and then the succession of loops is repeated, 85 so that any one loop is interlaced between two loops, one from each of the two wires at the other side of the stay from the first mentioned loop.

What I claim and desire to secure by Letters Patent of the United States is:

A wire garment stay, comprising a plurality of pairs of wires, the wire of each pair being formed into successive longitudinally arranged substantially semicircular loops, each semicircular loop terminating at 95 each end in a transversely extending substantially oval loop, the oval loops of a wire of each pair successively alternating with the oval loops of the other wire of that pair and the longitudinal loops of each wire 100 of each pair successively overlapping the longitudinal loops of the other wire of the respective pair, the oval loops of one pair being extended laterally in one direction and those of the other pair laterally in the opposite direction, and said oval loops being 105 interlaced so that the succession of oval loops consists first one of a wire of one pair,

one of a wire of the other pair, and then
one of the second wire of the first pair and
then one of the second wire of the second
pair, so that each oval loop is preceded by
5 an oval loop of one wire of the opposite pair,
and is followed by an oval loop of the sec-
ond wire of said opposite pair.

Signed in the presence of two subscribing
witnesses.

GAYLORD A. BARCLEY.
